UNITED STATES PATENT OFFICE.

CHARLES H. NOWACK, OF CHICAGO, ILLINOIS, ASSIGNOR TO AMERICAN CAN COMPANY, OF NEW YORK, N. Y., A CORPORATION OF NEW JERSEY.

CONTAINER.

1,354,914.

Specification of Letters Patent.

Patented Oct. 5, 1920.

Application filed December 21, 1917. Serial No. 208,311.

To all whom it may concern:

Be it known that I, CHARLES H. NOWACK, a subject of the Emperor of Austria-Hungary, residing in Chicago, in the county of 5 Cook and State of Illinois, have invented a new and useful Improvement in Containers, of which the following is a specification.

This invention relates in general to containers and has more particular reference 10 to containers of the character used ordinarily for the packaging of shoe polish and the like, although it will be manifest as the invention is better understood that it may be embodied in containers designed for a 15 wide variety of uses.

A principal object of the invention is the provision of a hermetically closed friction top container, which can be opened readily with the hand and without the necessity of 20 using any pry-off tools or implements.

A further object of the invention is the provision of such a container which will require no opening devices, consisting merely of a one-part body and a one-part cover.

25 A still further object of the invention is the provision of a container of pleasing appearance and economical manufacture.

Other objects and advantages of the invention will be apparent as it is better understood from the following description 30 when considered in connection with the accompanying drawing illustrating a preferred embodiment thereof.

On the drawing,
35 Figure 1 is a section taken through a container embodying my present invention;

Fig. 2 is a partial enlarged section taken similarly to Fig. 1;

40 Fig. 3 is an enlarged detail showing the action of the hand in removing the cover; and

Figs. 4 and 5 are perspective views showing the cover and body separated from each other.

45 For the purpose of illustrating my invention I have shown it embodied in a flat, circular container comprising a body 1 and a cover 2. The body 1 is of the usual cylindrical form and is provided at its top with

a curled wire edge 3. The cover consists 50 merely of a top or flat part 4 and a cylindrical flange 6. This flange 6 is offset above its bottom edge at 9 to engage the bead 3 and the lower part 8 of the flange extends straight down below the bead. The box is 55 closed by merely pushing the cover tightly about the edge and the parts are so constructed that the closure is an hermetic one. The box is opened by merely grasping it as shown in the drawing and pressing in on 60 two opposite sides of the cover. The engaged portions of the top and cover are of different flexibility with greater flexibility in the cover. The pressure of the fingers produces a slight deformation and the cover 65 springs off. Indeed the box may be opened if sufficient pressure is exerted at a single point in the depending part 8 of the cover flange.

It is thought that the invention and 70 many of its attendant advantages will be understood from the foregoing description, and it will be apparent that various changes may be made in the form, construction and arrangement of the parts without departing 75 from the spirit and scope of the invention or sacrificing all of its material advantages, the form hereinbefore described being merely a preferred embodiment thereof.

I claim:

1. The combination of a container body having its top edge formed in an outwardly turned curl, and a cover therefor formed with a shoulder adapted to rest on the top of said curl when the container is closed, the 85 edge of the cover being formed in a vertical flange which depends from the outer part of said shoulder and engages tightly around the outer side of said curl and extends below the bottom of said curl, said cover being disengageable from the body by pressing inwardly against said depending cover flange at a point below said curl of the body.

2. The combination of a container body having its top edge formed in an outwardly 90 turned curl, and a cover therefor formed with a shoulder adapted to rest on the top of said curl when the container is closed, the

edge of the cover being formed in a vertical flange which depends from the outer part of said shoulder and engages tightly around the outer side of said curl and extends below the bottom of said curl, the depending flange and body curl being of such relative flexibility and stiffness that pressure on the flange in an inward direction toward the

middle of the container will spring the cover from the body.

Signed in the presence of two subscribing witnesses.

CHARLES H. NOWACK.
